UNITED STATES PATENT OFFICE.

HENRY P. YOUNG, OF MILWAUKEE, WISCONSIN.

AUTOMATIC FIRE-ESCAPE.

No. 916,823.

Specification of Letters Patent. Patented March 30, 1909.

Application filed April 24, 1906. Serial No. 313,434.

To all whom it may concern:

Be it known that I, HENRY P. YOUNG, a citizen of the United States, residing at Milwaukee, in the county of Milwaukee and 5 State of Wisconsin, have invented a new and useful Improvement in Automatic Fire-Escapes, of which the following is a specification.

This invention relates to fire escapes, and 10 more particularly to automatic fire escapes; the object being to provide a portable fire escape which is very simple and cheap in construction and one which is very effective in use.

15 Another object of my invention is to provide an automatic brake in connection with the fire escape so that the speed of descent will be automatically regulated.

Another object of my invention is to provide 20 means for regulating the brakes so that the speed of descent can be regulated by the user.

With these objects in view, the invention 25 consists of the novel features of construction, hereinafter fully described, and pointed out in the claims.

In the drawings forming a part of this 30 specification:—Figure 1 is a perspective view of my improved fire escape partly broken away. Fig. 2 is an end view of my improved fire escape. Figs. 3 and 4 are detail views.

In the drawing A, indicates a frame provided with a bail A', adapted to fit over a hook B, secured in the window frame and 35 support the same. The oblique members A², of the frame are provided with apertured enlargements A³, in which is mounted a shaft C, provided with a spring actuated reel D, carrying a cable E, the end of which is 40 connected to a link F', of a belt F, adapted to be secured around the waist of the person and hold him securely while he is descending.

Mounted on the platform A⁴, of the frame 45 is a spring actuated grooved reel G, provided with a gear wheel H, adapted to mesh with a gear wheel I', secured on the upper end of a threaded shaft I, mounted in a threaded opening formed in an enlargement of the platform A⁴, of the frame. Rods J, carrying 50 coil-springs J', extend downwardly from the platform of the frame to each side of the threaded opening and are provided with brake shoes J², at their ends adapted to be held into engagement with the rims of the 55 reel by the springs J' so that the reel will be prevented from rotating fast. A cross bar

K, is mounted on the rods J, provided with a central opening K', through which the shaft I, is adapted to pass.

A head I², is secured to the lower end of the 60 shaft I, carrying balls I³, and provided with a recess I⁴, in which is mounted a spring actuated pin I⁵, adapted to engage a spiral groove K², formed in the under side of the cross-bar K, around the opening K', for the purpose 65 hereinafter described. An arm L, is mounted on a shaft M, in the frame having a forked end L', adapted to straddle the shaft I, on the bar K, and increase the pressure of the 70 springs J', against the brake shoes J², when pulled down by the cable E, which passes over a pulley L², carried by the arm L.

A cable N, is secured to the grooved pulley G and passes once or twice around the same, and passes down over a pulley O, mounted 75 on the frame having its other end passed through an eye in an arm F², of the belt F and is adapted to extend to the ground, so that the cog wheel can be revolved when desired by pulling on the cable so as to regulate 80 the pressure of the springs against the brake shoes.

The operation is as follows: The bail of the frame is hooked over the hook of the window-frame and the belt is then secured on the 85 body of the person, who lets himself out of the window, his weight on the cable causing it to unwind from the reel against the action of the spring, and at the same time the arm will be pulled down by the weight of the 90 person, causing the shoes to engage the rim of the reel allowing the person to descend at a moderate rate of speed. If the person wishes to descend faster, he pulls on the 95 cable carried by the reel, which causes the shaft passing through the cross bar to turn and release the tension of the springs on the shoes, which will cause the rate of descent to increase. The speed will continue to increase until the pin carried by the head has 100 traveled to the end of the spiral groove in the cross bar, which will lock the shaft against rotation thereby preventing the cross bar from being lifted off the spring any further so that the person in the belt will descend at 105 a predetermined speed.

Having thus fully described my invention, what I claim as new and desire to secure by Letters Patent is:—

1. In a fire escape, the combination with 110 a frame provided with a spring actuated reel, of a cable carried by said reel, brake shoes

adapted to engage said reel operated by the cable, a shaft for relieving the pressure of said brake shoes, a gear fixed to the shaft, a reel carrying a cable mounted on said frame 5 and a gear carried by the last mentioned reel engaging the gear of the shaft.

2. In a device of the kind described, the combination with a frame provided with a reel carrying a cable provided with a belt, 10 of rods mounted on said frame, carrying coil-springs and provided with brake shoes, a cross bar mounted on said rods, and an arm pivoted to the frame bearing on said cross-bar, provided with a pulley over which the 15 said cable passes, for the purpose described.

3. In a device of the kind described, the combination with a frame provided with a pulley, of rods mounted in said frame, springs arranged on said rods, a cross bar mounted 20 on said rod provided with an opening, surrounded by a spiral groove on its under side, brake shoes mounted on said rods, a threaded shaft mounted in said frame passing through said opening in said bar, a head secured to 25 the lower end of said shaft provided with a spring actuated pin adapted to engage the spiral groove of said bar, a gear wheel secured to the upper end of said shaft, a reel mounted on said frame provided with a gear wheel 30 meshing with said gear wheel, and a cable

connected to said reel, for the purpose described.

4. In a device of the kind described, the combination with a frame provided with a reel carrying a cable, spring actuated brake 35 shoes carried by said frame, a bar adapted to engage the spring of the shoes, provided with a central opening, an arm pivoted to said frame bearing on said bar, a pulley carried by said bar over which the cable passes, a 40 threaded shaft passing through said bar mounted in said frame provided with a head adapted to engage said bar and means for rotating said shaft, for the purpose described.

5. In a device of the kind described, the 45 combination with a frame provided with a reel carrying a cable, of spring actuated brake shoes adapted to engage said pulley, a bar mounted on the spring of the shoes, an arm provided with a pulley pivoted to said 50 frame bearing on said bar, the cable of the reel passing over said pulley and a screw carried by the frame provided with a head adapted to engage the bar arranged on the springs of the shoes, for the purpose de- 55 scribed.
